UNITED STATES PATENT OFFICE.

HENRY HAMMENSTEDE, OF NEW YORK, N. Y.

IMPROVEMENT IN PHOTOGRAPHIC SCREENS AND REFLECTORS.

Specification forming part of Letters Patent No. **155,944**, dated October 13, 1874; application filed September 9, 1874.

To all whom it may concern:

Be it known that I, HENRY HAMMENSTEDE, of New York, in the State of New York, have invented a new and improved Light-Condensator, of which the following is a specification:

The nature of my invention consists in the combination of two hollow reflectors, one above the other, capable of turning on suitable centers, so constructed that the light is concentrated in the upper reflector at any particular point, while the shadows are modified or lessened by the position of the lower reflector.

The accompanying drawing represents a front view of a light-condensator embodying my invention.

A is a concave reflector, about five feet in diameter and ten feet focus, hung in a suitable frame, C, on centers *v v*, which enables said reflector to be placed in the desired position to concentrate the light in any place. This frame C is attached, by means of a screw, *n*, to another frame, D, in such a manner as to be capable of turning around said screw *n*. In the lower frame D a hollow reflector, B, is hung on screws *w w*.

The reflectors A and B can be made of any light material, such as wood or pasteboard, and lined with tin-foil. The reflector B I prefer to make about three feet high and of twenty feet radius.

This light-condensator is particularly intended for the use of photographers. When a portrait is to be taken, the apparatus is placed from seven to eight feet from the person. The light is concentrated by the upper reflector A on the face of the person, while the shadows are modified or lessened by the position of the lower reflector B.

What I claim as my invention, and desire to secure by Letters Patent, is—

In a photographic screen and reflector, the combination of a concave reflector, A, supported in a frame, C, and turning on a central pin, *n*, with a segmental pivoted reflector, B, supported on the lower frame D, all arranged in the manner and for the purpose substantially as set forth.

HENRY HAMMENSTEDE.
